CONTAINER

Daniel Belcher, Minneapolis, Minn., assignor to
 Bemis Bro. Bag Co., Minneapolis, Minn., a corporation of Missouri

Application December 19, 1935, Serial No. 55,246

7 Claims. (Cl. 229—55)

This invention relates to new and useful improvements in containers, and more particularly to flexible walled containers such as paper bags, adapted to contain a finely ground or pulverized material as, for example, flour, and various other articles.

Since the advent of "Cellophane", a great many food articles are now wrapped or packed with this material, primarily, because it greatly enhances the appearance of the package, and, furthermore, because it is very inexpensive. There is one objection, however, to the use of "Cellophane" for certain purposes, and that is, it has a tendency to become more or less brittle from age, after which it readily cracks and thereby loses its usefulness, particularly when the "Cellophane" itself provides the walls of the container. The inherent nature of the material is also such that adhesives and gums do not readily penetrate the surface thereof, whereby ordinary adhesives and gums cannot readily be used to secure the folded walls thereof in closing relation, because it requires too long a time for the adhesive to set sufficiently to permit the package to be handled without danger of the gummed walls thereof becoming unfastened or opening.

In the present invention, I propose to use the "Cellophane" or other similar material in connection with a conventional container or paper bag, whereby it provides only an outer enclosing member therefor, and does not become a structural part of the bag itself. By thus enclosing the package in "Cellophane" greatly improves its appearance, and also renders it less subject to attracting dust and other foreign matter, when handled. The "Cellophane" enclosing member is desirably applied to the tube from which the bag body is formed before the bottom of the bag is constructed, and the bag bottom is then formed in the usual manner, after which the bag is completed to receive the material to be packed therein.

An object of the present invention, therefore, is to provide a container or paper bag having an outer enclosing member of "Cellophane" secured thereto, whereby when the bag has been filled and sealed, it will have the appearance of being wrapped in "Cellophane."

A further object is to provide a paper bag having its body portion enclosed in an outer member of "Cellophane" or a similar material, the primary function of which is to give the sealed package or container the appearance of being wrapped in "Cellophane", and wherein the strength of the package or bag is not impaired

as the "Cellophane" preferably does not, in any way, constitute a structural part of the bag body.

Other objects of the invention reside in the particular manner in which the outer "Cellophane" enclosing member is applied to the tube from which the bag is constructed, whereby the operation of constructing the bag bottom may be performed on a bottoming machine in the usual manner; in the relative sizes of the outer enclosing member and the inner member, whereby the upper edge or top of the outer member terminates short of the upper portion of the inner member, thereby to facilitate securing the bag top walls in sealing relation by a suitable adhesive; and in the provision of a paper bag having an outer enclosing member fitting over the body thereof and suitably secured thereto, said outer member being so arranged that when the bag top is closed and sealed, the paper bag which actually supports the material, will be substantially entirely enclosed in a "Cellophane" wrapper, whereby the appearance of the bag is greatly improved, and whereby the package may also be rendered more or less water-proof.

Other objects of the invention will appear from the following description and accompanying drawing and will be pointed out in the annexed claims.

In the accompanying drawing there has been disclosed a structure designed to carry out the various objects of the invention, but it is to be understood that the invention is not confined to the exact features shown as various changes may be made within the scope of the claims which follow.

In the drawing:

Figure 1 is a view showing a bag tube with the outer enclosing member applied thereto;

Figure 2 is a similar view but showing the bag with its bottom completed;

Figure 3 is a perspective view, showing the bag opened for filling;

Figure 4 is a view of the upper portion of a filled bag showing the bag top walls partially folded to close the bag top;

Figure 5 is a perspective view showing a sealed bag;

Figure 6 is a view similar to Figure 1, but wherein the printed material is applied directly to the "Cellophane" or outer enclosing member and not directly upon the paper bag;

Figure 7 is a view showing a slightly modified construction wherein the lower portion of the outer enclosing member is provided with means for completely concealing the bag bottom;

Figure 8 is another view of the form shown in Figure 7, looking at it from the opposite side; and

Figure 9 is a view showing the bag bottom completely concealed by the outer enclosing member.

In the selected embodiment of the invention here shown, there is illustrated in Figure 1, for purposes of disclosure, a bag generally indicated by the numeral 2, shown having its lower end slitted as at 3 in the usual manner to permit 10 folding the lower wall portions thereof, as shown in Figure 2, to construct the bottom 4 of the bag.

An important feature of the present invention resides in the unique construction of the bag body which, as shown in the drawing, is provided 15 with an outer enclosing member, generally indicated by the numeral 5. This covering member is of a suitable material such as "Cellophane," which preferably is transparent so that the printed matter, indicated by the numeral 6, 20 which usually is applied directly to the walls of the bag body, may be clearly seen through the outer enclosing member.

The lower edge 7 of the outer enclosing member 5 preferably terminates short of the lower edge 8 of the bag blank 2, as clearly illustrated in Figure 1, whereby the lower portions of the bag tube walls are folded into closing relation, and certain portions of said walls will directly contact other portions of said walls whereby they 30 may readily be secured together in sealing relation with ordinary adhesives or gums. The lower portion of the enclosing member 5 is preferably secured to the bag tube by a suitable adhesive, indicated at 9 in Figure 1, and the lower edge 7 of the covering member 5 is preferably so spaced from the lower edge 8 of the bag tube, that when the bottom is formed, the lower edge portion of the "Cellophane" will constitute, in effect, a portion of the bag bottom, as will be readily understood by reference to Figure 2.

The upper edge 11 of the outer enclosing member 5 also preferably terminates short of the upper edge 12 of the bag top to permit portions of the bag top walls to be folded into direct contact with one another to facilitate securing them together in sealing relation by a suitable adhesive or gum.

A notch 13, preferably V-shaped, may be provided in the upper edge 11 of the enclosing member 5. This notch will appear as shown in Figure 4, when the bag top walls are partially folded into closing relation. In Figure 4, it will be noted that the end walls 14 and 15 of the bag top have been folded inwardly, one over the other, whereby flaps 16 and 17 are formed in the upper portions of the front and rear walls 10 and 20, respectively. Because of the V-shaped notch 13 provided in the upper edge of the enclosing member 5, the terminal of the flap 16 is exposed, as shown at 18 in Figure 4, which permits the terminal 19 of the flap 17 to be folded over the terminal 18 of the flap 16 in direct contact therewith. Before the flap 17 is folded over the bag top, a suitable gum is applied to the inner surface thereof, as indicated at 21 in Figure 4, which secures the flap 17 to the previously folded bag top walls, as shown in Figure 5.

The upper edge portion of the outer enclosing member 5 is also preferably secured to the walls of the bag top by a suitable gum, as indicated at 22, thereby to prevent the upper edge of the "Cellophane" enclosing member from fraying or becoming torn.

Figures 7, 8, and 9 illustrate a slightly modified 75 construction wherein the outer enclosing mem-

ber 5 is provided at its upper end adjacent to the rear wall 20 with an upstanding portion 23, preferably triangular in shape, whereby its shape will conform substantially to the pointed terminal 19 of the flap 17 of the rear wall. The 5 triangular portion 23 conceals the tip 19 of the flap 17 when the bag top is completely closed, whereby none of the wall surfaces of the bag top walls are exposed, as is shown at A in Figure 5.

The front side of the "Cellophane" enclosing member 5 may also be provided with a depending portion 24, as best illustrated in Figure 7, the width of which is substantially equal to the spacing between the slits 3-3 in the lower portion of the blank or tube 2. In Figures 7 and 8, 15 it will also be noted that the lower marginal edge 25 of the enclosing member 5 is spaced relatively closer to the lower edge 8 of the tube 2 than it is in the forms shown in the previous figures. By constructing the lower portion of 20 the enclosing member 5 as shown in Figure 7, when the bottom of the bag is formed, the lower edges of the enclosing member 5 will be completely concealed, as best shown in Figure 9, wherein it will be noted that the paper or material of the bag proper, which constitutes the bottom 4 of the bag, will be completely concealed by the "Cellophane" enclosing member.

The triangular portion 23 and also the depending portion 24 of the outer enclosing member 5 are 30 suitably secured to the adjacent surfaces of the bag tube or blank, as indicated at 26 and 27, in Figures 7 and 8, respectively. Thus, by constructing or shaping the outer "Cellophane" enclosing member 5, as shown in Figures 7, 8, and 9, the 35 entire surface of the bag proper will be concealed or enclosed within the "Cellophane" wrapper, and the completed sealed bag will have the appearance of being wrapped in "Cellophane" in the usual manner.

In the description of the invention, I have referred to the outer enclosing member as being constructed of "Cellophane." It is to be understood, however, that any other material of a similar character may be employed without departing from the scope of the invention. The important feature of the invention, as previously stated, resides in fitting a "Cellophane" enclosing member over the bag body before forming the bottom thereof, whereby when the bag is filled and the top thereof is closed and sealed, the bag body will be enclosed in "Cellophane" without necessitating any additional packaging operations, as when the "Cellophane" is applied to the bag body after the bag has been filled and sealed. Also, by applying the "Cellophane" to the bag blank or tube, as herein set forth, the sealed bag may be enclosed in a "Cellophane" wrapper without materially increasing the packaging cost.

The outer enclosing member 5 is preferably secured to the bag tube at its upper and lower portions only, as illustrated in the drawing, whereby the "Cellophane", when the bag has been filled and sealed, will have the appearance of being wrapped around the body of the bag in the usual manner. In other words, the "Cellophane" will not be secured to the entire outer surface of the bag body, as it would be in a bag constructed of laminated material, comprising an outer layer of transparent material, such as "Cellophane". It 60 is to be understood, however, that the particular manner of securing the "Cellophane" to the bag tube may be varied, as desired, without departing from the scope of the invention.

In some instances, it may be found desirable to 75

apply the printed matter, to appear on the bag, directly to the outer "Cellophane" enclosing member, as illustrated at 28 in Figure 6. However, because of the transparent nature of the "Cellophane", the printed matter may be applied either directly to the bag body, or to the "Cellophane", without changing the appearance of the completed package.

I claim as my invention:

- 10 1. A paper bag having an outer enclosing member of "Cellophane" secured thereto, the upper edge of which terminates short of the upper edge of the bag top, whereby portions of the bag top walls may be folded into direct contact with one another to facilitate sealing the bag mouth.
- 15 2. A paper bag having an outer enclosing member of "Cellophane" fitted thereover and suitably secured thereto, the lower portion of said enclosing member terminating short of the bottom edge 20 of the tube from which the bag is formed, whereby the lower edge portions of the tube may be folded into direct contact with one another to facilitate constructing the bag bottom.
- 25 3. A paper bag having an outer enclosing member of "Cellophane" fitted thereover, the lower portion of which constitutes a portion of the bag bottom, and the upper portion of said enclosing member being so arranged with respect to the bag top that portions of the bag top walls may be 30 folded into direct contact with one another to facilitate closing and sealing the bag top.
- 35 4. A paper bag formed from a tube having a "Cellophane" wrapper fitted thereover, the lower portion of said wrapper being arranged to fold simultaneously with the walls of the tube blank 35 when constructing the bottom of the bag, and the upper portion of said wrapper terminating short of the upper edge of the bag top and having a notch therein exposing a portion of one of the 40 walls of the bag top when said wall is folded into closing relation, whereby an oppositely disposed wall portion may be folded into direct contact

with said exposed wall and secured thereto by a suitable gum.

5. A paper bag formed from a tube having a "Cellophane" wrapper fitted thereover, the lower edge of which terminates short of the lower edge 5 of the tube to facilitate constructing the bag bottom, and the upper portion of said wrapper terminating short of the upper edge of the bag top and having a V-shaped notch therein, said V-shaped notch exposing a portion of one of the 10 walls of the bag top, when said wall is folded into closing relation, whereby an oppositely disposed wall portion may be folded into direct contact with said exposed wall and secured thereto by a 15 suitable gum.

6. A paper bag formed from a tube having a "Cellophane" wrapper fitted thereover, the lower edge of which terminates short of the lower edge 20 of the tube to facilitate constructing the bag bottom, and the upper portion of said wrapper terminating short of the upper edge of the bag top and having a notch therein at one side of the bag 25 and an upwardly extending projection at the opposite side of the bag, and the lower edge of the wrapper having a depending portion, said upwardly extending and depending portions cooperating with the body of the wrapper to completely enclose the top and bottom of the bag, when the bag is closed and sealed.

7. A container formed from a paper tube open 30 at both ends, and having an outer transparent enclosing member of a cellulose, adhesive repellent material, such as "Cellophane", suitably fitted thereover, the ends of said member terminating slightly inwardly of the ends of the tube blank, 35 thereby to expose the opposite end portions of the tube, and whereby said exposed end portions may be gummed and folded into direct contact with one another to form the bottom of the container, and subsequently the closed top thereof. 40

DANIEL BELCHER.
